WEATHER INDICATING INSTRUMENT

C. Douglas Turnbull, Chicago, Ill., assignor to Airguide
Instrument Company, Chicago, Ill., a corporation of
Illinois

Filed Aug. 21, 1969, Ser. No. 18,799

Term of patent 14 years

Int. Cl. D10—07

U.S. Cl. D52—7

FIG. 1 is a side perspective view of the weather indicating instrument; and

FIG. 2 is a front perspective view of the weather indicating instrument.

The undisclosed side of the weather indicating instrument is a mirror image of the side shown, and the rear thereof is flat and plain in appearance.

I claim:

The ornamental design for a weather indicating instrument, as shown and described.
